COMPRESSOR

John W. White, South Bend, Ind., assignor to
 Bendix Aviation Corporation, South Bend,
 Ind., a corporation of Delaware

Application November 19, 1938, Serial No. 241,300

1 Claim. (Cl. 230—45)

This invention relates to compressors, and particularly to a rotary air compressor of the type comprising a working cylinder or casing within which is mounted eccentrically a rotor having a plurality of slots in which are adapted to slide vanes that contact with the inner surface of the cylinder.

It is the principal object of my invention to provide certain improvements in such a compressor whereby its general efficiency is enhanced.

In the preferred embodiment of my invention there is provided a compressor, the vanes of which function to effect the compression of the air or gas in two stages.

Yet another object of the invention is to provide a compressor of the above type wherein the reciprocable vanes thereof serve to compress the gas during the first revolution of the rotor, and again serve to compress the same gas to a higher degree of compression during a subsequent revolution of the rotor.

Yet another object of the invention is to provide a compressor which is simple and compact in construction, efficient in operation and inexpensive to manufacture.

Other objects of the invention and desirable details of construction and combinations of parts will become apparent from the following detailed description of certain embodiments of the invention, taken in conjunction with the accompanying drawings illustrating said embodiments, in which:

Figure 1 is a longitudinal sectional view of the compressor constituting a preferred embodiment of my invention;

Figure 2 is a transverse sectional view of the compressor disclosed in Figure 1, taken on the line 2—2 thereof;

Figure 3 is a view, similar to Figure 1, disclosing another embodiment of a two-stage compressor; and

Figure 4 is a transverse sectional view of the compressor disclosed in Figure 3, taken on the line 4—4 thereof.

Referring to Figures 1 and 2, there is disclosed a compressor 10 including a casing 12 in which is contained a rotor 14 mounted upon a power driven shaft 16, the ends of which are journaled in end plates 18 and 20 secured to the casing. The rotor 14, which is eccentrically mounted within the casing, is provided with radially disposed slots in which are slidably mounted vanes 22. A port 24 in the top of the casing provides what is termed a first inlet, and a port 26 in the end wall 18 provides a second inlet. A port 28

in the bottom of the casing provides what is termed a first outlet, and a port 30 in the end wall 18 provides a second outlet. Obviously, the construction might be altered to incorporate the second inlet and second outlet ports in one or the other of the end members 18 and 20.

Describing now the operation of this compressor and, incidentally, completing the description thereof, during the first revolution and succeeding revolutions of the rotor 14, air, or other medium to be compressed, is drawn in the first inlet port 24, the casing 12 being flared at 32 and provided with a lining 34 slotted, as disclosed in Figure 1, to facilitate the flow of air. This air is then compressed by the curved top walls of the moving vanes 22 and is forced out of the casing through an outlet duct 36 and the aforementioned first outlet port 28. Leaving the port 28, the compressed air enters a conduit 38, preferably wrapped closely about the casing 12. However, the air might also be passed through a duct, not shown, in the body of the casing.

Continuing the description of the cycle of operations, the compressed air passes from the conduit 38 into the second inlet port 26, disclosed in Figure 1, thence through an elongated duct 40 in the end plate 18 and into a compartment 42 in the uppermost slot below the uppermost vane 22. Such a compartment results from the outward movement of the vane, which is maintained in contact with the inside wall of the casing 12 by centrifugal force. With inward movement of the aforementioned vane, that is, to a position nearer the center of the compressor, the compressed air in the compartment is further compressed and is then forced into at least one of the ports 44 in the inner wall of the rotor 14. The compressed air upon entering one of the ports 44 forces open a spring loaded ball check valve 46, the air then passing through a duct 48 and a port 50 in the shaft 16 and thence through a slot 52 in a sleeve 54 surrounding the shaft. From the slot 52 the compressed air passes into the second outlet port 30 and thence into a conduit 56 leading to a storage tank or other depository. As clearly disclosed in Figure 1, check valves 46 are housed within the ports 44 and are urged by springs 58 to seat upon members 60, threadedly mounted within the ports.

There is thus provided a rotary compressor wherein the vanes thereof serve to compress the same gas in two distinct stages, the construction and arrangement of the parts of the mechanism, such as the capacity of the compartments 42 and particularly the strength of the check valve

springs 58, being such as to effect one stage of the compression during one revolution of the rotor and a second stage of the compression of the same gas with a succeeding revolution of the rotor. Referring to Figure 2, it will be noted that during the counterclockwise travel of one of the vanes from the first inlet port 24 to its lowermost position the portion of gas located between two adjacent vanes is compressed during the first revolution of the rotor and is then transmitted, through the conduit 38, back to the uppermost of the compartments 42. In all probability during the next succeeding revolution of the rotor, a large portion of the aforementioned portion of gas is again and further compressed, probably during the inward movement of the lowermost vane disclosed in Figure 2 from the position there shown.

There is disclosed in Figures 3 and 4 another embodiment of my invention. All of the parts 20 of this mechanism are duplicates of those disclosed in Figures 1 and 2, and accordingly are given the same reference numerals. The compressor here disclosed differs from the mechanism of Figures 1 and 2 by the omission of 25 the check valves and cooperating ducts and ports in the shaft 18 and end wall 18 and the substitution in their stead of a diagonally extending second outlet duct 62 in the end wall 28. As clearly disclosed in these figures, this duct is positioned 30 so as to receive the gas when the same is compressed to the maximum.

Although this invention has been described in connection with certain specific embodiments, the principles involved are susceptible of numerous other applications that will readily occur to persons skilled in the art. The invention is, therefore, to be limited only as indicated by the scope of the appended claim.

I claim:

A rotor compressor comprising a casing having end members, a shaft extending through the casing and journalled in said end members eccentrically with respect to said casing, said shaft being ported at one of its ends to provide a plurality of ports and a plurality of ducts in said shaft connected with said ports and said shaft being shaped to provide a plurality of spaced valve receiving openings communicating with said ducts, a slotted rotor member eccentrically mounted within the casing upon the shaft, said rotor member being shaped to provide a plurality of spaced valve receiving openings communicating with the aforementioned valve receiving openings in the shaft and, together with the major portion of the inner walls of the casing, outlining a chamber, radially disposed vane members reciprocally mounted within the slots of said rotor member, and contactible with the inner walls of the casing, an inlet port in the upper part of said casing communicating with the aforementioned chamber, an outlet port in the lower part of said casing also communicating with said chamber, an inlet port in the upper part of one of the end members, a duct in said end member interconnecting said last mentioned port and the slots of the rotor when the latter is moving, an outlet port in one of the end members, said port communicating with the ports in said shaft, check valve members housed within the aforementioned valve receiving openings in the shaft and rotor and a conduit interconnecting said second mentioned inlet port with the first mentioned outlet port.

JOHN W. WHITE.
